(57) **CLAIM**

I claim the ornamental design for a small dog pool float, as shown and described.

DESCRIPTION

FIG. 1 is a top perspective view of a small dog pool float, shown with the hood portion in a collapsed position;

FIG. 2 is a front view thereof;

FIG. 3 is a rear view thereof;

FIG. 4 is a right side elevation view thereof;

FIG. 5 is a left side elevation view thereof;

FIG. 6 is a top plan view thereof;

FIG. 7 is a bottom view thereof;

FIG. 8 is an in-use perspective view thereof;

FIG. 9 is a front view thereof;

FIG. 10 is a rear, top perspective view of the small dog pool float, shown with the hood in an expanded position;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom view thereof.

The broken line showing of a dog in FIGS. 8 and 9 is for the illustrative purpose of depicting the float in use, and forms no part of the design claim.
